W. J. COLEBERT

HEDDLE SCREW HOOK

Filed Aug. 9, 1923

Inventor
William J. Colbert
By Thomas A. Jenkins, Jr.
Attorney

UNITED STATES PATENT OFFICE.

WILLIAM J. COLBERT, OF FALL RIVER, MASSACHUSETTS.

HEDDLE SCREW HOOK.

Application filed August 9, 1923. Serial No. 656,605.

To all whom it may concern:

Be it known that I, WILLIAM J. COLBERT, a citizen of the United States, residing at Fall River, in the county of Bristol and 5 State of Massachusetts, have invented certain new and useful Improvements in Heddle Screw Hooks, of which the following is a specification.

My invention relates to improvements in 10 heddle frames, more particularly to improved means for securely locking the heddle shafts therein, and improvements in locking screw hooks and in the art of their manufacture.

15 I am aware that hitherto straight looped heddle hooks have been employed for the purpose of supporting the heddle shafts in the heddle frames and holding the heddles apart. These hooks, however, have only 20 been able to lock the heddle shafts in one vertical direction. When the heddle frame is suitably attached to the harnesses and the loom operated, there is apt to be a chafing of heddle frames and consequent vibration, 25 as well as much vibration in all directions from the general operation of the loom itself. It is apparent that with the use of the former hooks, the heddle shafts are only prevented from movement towards the median 30 line of the heddle frames and laterally until unhooked, but are free to move vertically away from the median line thereof. As the heddle shafts are usually inherently resili- 35

the vertical plane of the operating frame, as well as sidewise therein. Much wear and tear takes place both on the heddle shafts and hooks. The vibration is sometimes so great that the heddle shafts will jump out 40

of these looped hooks, and in time the end of the hooks wear through, leaving the resilient heddle shafts loose in all directions, and often the heddle shafts themselves become 45 worn and break. It is obvious that as the

two heddle frames normally function very close to each other, a jumping or horizontally vibrating shaft will often catch against the frame of the closely co-operating heddle, causing a harness smash. Very 50

often the shafts are bent or broken and the heddles either broken or badly twisted. Broken selvages or other defects in the cloth are caused, producing second-quality goods. Much time is lost in resetting the heddles in 55 the drawing-in room, causing a lack of production, as well as badly trying the patience

of the weaver. My invention comprises a heddle hook wherein the end of the head of the hook is bent approximately at right angles to itself and obliquely toward the 60 threaded stem thereof, in such a manner that the hook may be turned to permit insertion of the heddle shaft therein, and when the heddle shaft is inserted, may be further turned so that the bent locking end thereof 65 engages the heddle shaft and locks it against vertical as well as horizontal vibration. One object of my invention, therefore, is to provide a suitable means for readily and tightly locking the heddle shaft against vibration, 70 thus preventing wear thereof and harness smashes.

As hereinafter explained and illustrated, the horizontal vibration of the heddle shaft will cause it to act as a lever in pivoting the 75 hook. A dead center line will soon be reached, however, where the turning vibration of the shaft will be equal in both directions, and the shaft will no longer act as a lever to turn the hook. The obliquely disposed bent over locking end will, however, at this point still serve to prevent the heddle shaft from any vibration in any direction. A further object of my invention is to provide a heddle hook which will not unlock 80 under vibration. In addition, if a right hand thread is used, and the end bent obliquely clockwise thereto any loosening of the thread from vibration will cause deeper engagement thereof. 85

Further objects of my invention are to provide a screw hook of improved construction, and improvements in the art of screw manufacture.

These and such other objects of my invention as may hereinafter appear will be best understood from a description of one embodiment thereof such as is shown in the accompanying drawings.

In the drawings, Fig. 1 is a perspective view of a heddle frame, showing the hooks in locked position theron.

Fig. 2 is a perspective view of a portion of the lower side bar of the frame showing the hook locking the heddle shaft thereto.

Fig. 3 is a perspective view of a portion of the lower side bar of the frame showing the hook in unlocked position, thus permitting withdrawal of the heddle shaft therefrom.

Fig. 4 is a perspective view of my improved screw hook.

Fig. 5 is a plan view showing the hook

engaging the heddle shaft in locked position.

Fig. 6 is a plan view showing the bent locking end of the hook still engaging the heddle shaft after horizontal vibration of 5 the shaft has forced the hook to a dead center line.

In the drawings, wherein like characters of reference indicate like parts throughout, 10 generally indicates the heddle frame, comprising the usual side bars 11 and 12, and end bars 13 and 14 preferably constructed of wood, suitably joined together to form the usual rectangular frame. The heddle shafts 16 are suitably inserted 15 lengthwise of the frame 10, and locked in position thereon by any suitable means, in the embodiment shown by the locking pins 17. Thin rectangular shafts which are inherently resilient as shown, are the type 20 normally used. The shafts 16 are inserted through the end eyes 18 of the heddles 19, thus mounting the heddles thereon. 20 generally indicates my improved locking screw hook. In Fig. 1, I have shown one locking 25 hook 20 used on each of the side bars 11 and 12 of the frame. This is usually sufficient to lock the entire heddle shaft 16 against vertical and horizontal vibration. When desired, the former type of hook as illustrated at 21 with the locking ends 22 thereof merely looped over in a similar plane, may be used to further assist in preventing horizontal vibration.

My improved locking screw hook, as 30 shown in Fig. 4 is made as follows: A piece of wire is suitably threaded at one end thereof as usual, as shown in the embodiment, with the right hand thread 25. The other end of the wire is first looped over on itself 35 in the same plane to form the hook portion 26, the downwardly extending portion 27, and opposed threaded stem 29. The extreme end of the downwardly extending portion 27 is then bent at approximately right angles 40 to itself toward the threaded stem 29 and obliquely to the vertical plane of the looped hook portion 26, downwardly projecting portion 27 and threaded stem 29, preferably at an angle to said plane of about 45° to 45 form the locking lug or tip 28. Better results are obtained by bending the lug 28 in a direction opposite to the advance of the thread 25, thus in the right hand threaded embodiment to the left or towards the slack side of the thread. The reason for this will 50 be explained later.

The manner in which my improved hook provides for the first time means to prevent vibration of the heddle shaft in any direction and co-operates with the other portions of the heddle frame to provide an improved heddle frame, will be best understood from the following description of its mode of operation: I will describe the operation of the 55 embodiment shown, which as explained has

a right hand thread, with the locking end 28 thereof bent counter clockwise in a direction opposite to that of the thread. The locking screw hook 20 is threaded the desired amount into the usual wooden side bar 12 where desired and until the locking lug 28 thereof is approximately parallel to the side bar 12, as indicated in Fig. 3. As indicated, a space 30 is thus left open between the threaded stem 29 thereof and the locking lug 28. The heddle shaft 16 may then be lifted up and inserted vertically through this space 30 into the space 32 formed between the stem 29 and the downwardly extending portion 27. The hook 20 is then partially unscrewed by turning it counter-clockwise to the left approximately 45°, thus forcing the locking lug across the heddle shaft 16, and completely enclosing the heddle shaft 16 in the locking space 32 as indicated in Fig. 2, or as shown in plan in Fig. 5. To position the locking space 32 for vertical withdrawal of the heddle shaft 16 through the space 30, the hook 20 is screwed clockwise to the right approximately 45° to the original position indicated in Fig. 3. If desired, the heddle shaft 16 may be longitudinally inserted through the locking space 32 of the screw hooks 20 without turning of the threads 25 thereof.

The plan views shown in Figs. 5 and 6, illustrate additional features of my invention. When in locking position, Fig. 5, the hook 20 is turned until the locking end 28 is at approximately right angles to the heddle shaft 16, securely locking the heddle shaft against vertical and horizontal movement. It is obvious, however, that the lateral vibration of the heddle shaft 16 will cause said shaft to act as a lever to pivot the looped hook 26, downwardly projecting portion 27 and locking end 28 around the threaded stem 29, until the looped hook 26 reaches the dead center line 34 illustrated in Fig. 6, where it will stop, the horizontal vibrative force then being all resolved to bear laterally outwards against the downwardly projecting side 27 at right angles to the heddle shaft 16, thereby preventing further pivotal movement thereof. It will be observed, however, that when this dead center line is reached, the locking end 28 of the hook 20 being bent obliquely at an angle of 45° to the plane of the looped hooked portion 26 and downwardly projecting portion 27, will still function as illustrated in Fig. 6 to secure said heddle shaft 16 against vertical vibration. The reason why the locking end 28 is bent in an opposite direction to the direction of the thread 25 now becomes apparent. In moving the looped hook 26 and downwardly projecting side 27 from the position shown in Fig. 5 to that shown in Fig. 6, the vibrative action is resisted by the thread 25 functioning against the wood.

It is obvious that I have provided a locking screw hook especially adapted for use with heddles, improvements in the manufacture thereof, and that for the first time in a 5 heddle frame I have provided in combination with the other parts thereof means to lock the heddle shaft against vibration in any direction.

It is understood that my invention is not 10 limited to the specific embodiment shown and that various deviations may be made therefrom without departing from the spirit and scope of the appended claims.

What I claim as new and desire to secure 15 as Letters Patent is:

1. In heddle frames, the combination of a rectangular wooden frame, heddle shafts mounted longitudinally therein, heddles mounted transversely of said shafts, and 20 means to lock the resilient center portions of the heddle shafts to the frame, comprising locking screw hooks having integral locking ends bent over to prevent the vibration of said heddle shafts in any direction. 25 2. In heddle frames, the combination of a rectangular wooden frame, having longitudinally extending side bars, heddle shafts mounted longitudinally therein, heddles mounted transversely of said shafts, and 30 means to lock the resilient center portions of the heddle shafts to the frame against vibration in any direction, comprising locking screw hooks, having stems threaded into the longitudinal side bars of said 35 frames, semi-circular looped hook portions to prevent movement of said heddle shafts toward the median line of said frame, portions projecting downwardly therefrom in the same plane to cooperate 40 with said threaded stems to enclose said shafts against sidewise movement, and locking ends bent approximately at right angles to the downwardly projecting portions, and obliquely towards the threaded 45 stems at approximately 45° to the vertical plane of the threaded stems, the looped hook and downwardly projecting portions, to prevent vertical movement of the said heddle shafts away from the median line of said 50 frame, said locking screw hooks permitting on slight turning thereof withdrawal of the heddle shafts therefrom between said threaded stems and locking ends when the locking ends are turned to positions approximately parallel to said shafts. 55

3. In heddle frames, the combination of a rectangular wooden frame, having longitudinally extending side bars, heddle shafts mounted longitudinally therein, heddles 60 mounted transversely of said shafts, and means to lock the resilient center portions of the heddle shafts to the frame against vibration in any direction, comprising locking screw hooks, having stems threaded into the 65 longitudinal side bars of said frames, semi-

circular looped hook portions to prevent movement of said heddle shafts toward the median line of said frame, portions projecting downwardly therefrom in the same plane to co-operate with said threaded stems to 70 enclose said shafts against sidewise movement, and locking ends bent approximately at right angles to the downwardly projecting portions, and obliquely towards the threaded stems at approximately 45° to the vertical plane of the threaded stems, the looped hooks and downwardly projecting portions in the opposite direction to the 75 thread of the stem, to prevent vertical movement of said heddle shafts away from the median line of said plane, said locking screw hooks permitting on slight turning thereof withdrawal of the heddle shafts therefrom between said threaded stems and locking ends when the locking ends are turned to positions approximately parallel to said shafts. 80 4. In heddle frames, the combination of a rectangular wooden frame having longitudinally extending side bars, heddle shafts mounted longitudinally therein, heddles mounted transversely of said shafts, and means to lock the resilient center portions of the heddle shafts to the frame against vibration in any direction, comprising locking 85 screw hooks, having stems threaded into the longitudinal side bars of said frames, looped hook portions to prevent movement of said heddle shafts toward the median line of said frame, portions projecting downwardly therefrom to co-operate with said threaded stems to enclose said shafts against sidewise movement, and locking ends bent obliquely from the downwardly projecting portions toward the threaded stems and obliquely to 90 the vertical plane of the threaded stems, to prevent vertical movement of said heddle shafts away from the median line of said frame, said locking screw hooks permitting on slight turning thereof withdrawal of the heddle shafts therefrom between said 95 threaded stems and locking ends. 100 5. As a new article of manufacture, a locking screw hook, comprising a threaded stem portion, a semi-circular hooked portion looped over from the threaded stem in the same vertical plane, a portion projecting downwardly from the other end of said hooked portion in the same plane, and a locking end bent approximately at right angles to the downwardly projecting portion toward the stem, and obliquely at approximately 45° to the vertical plane of the stem, the hooked portion and downwardly projecting portion. 115 6. As a new article of manufacture, a locking screw hook, comprising a threaded stem portion, a semi-circular hooked portion looped over from the threaded stem in the same vertical plane, a portion projecting downwardly in the same plane, from the 120 125 130

other end of said hooked portion, and a locking end bent approximately at right angles to the downwardly projecting portion toward the stem, and obliquely at approximately 45° in the opposite direction to the thread of the stem to the vertical plane of the stem, the hooked portion and downwardly projecting portion.

7. As a new article of manufacture, a locking screw hook, comprising a threaded

stem portion, a hook portion looped over from the threaded stem, a portion projecting downwardly from the other end of said hooked portion, and a locking end bent obliquely from the downwardly projecting portion toward the threaded stem, and obliquely to the vertical plane of the threaded stem. 15

In testimony whereof I affix my signature.

WILLIAM J. COLBERT.
